US00D726831S

(12) **United States Design Patent**
Lee et al.

(10) **Patent No.:** US D726,831 S
(45) **Date of Patent:** ** Apr. 14, 2015

(54) **GAME CONTROLLER**

(75) Inventors: **Noel Lee**, Las Vegas, NV (US);
Kendrew Lee, Hong Kong (HK); **Minki Bang**, Daly City, CA (US)

(73) Assignee: **Monster, LLC**, Las Vegas, NV (US)

(**) Term: **14 Years**

(21) Appl. No.: **29/430,377**

(22) Filed: **Aug. 24, 2012**

(51) LOC (10) Cl. **21-01**

(52) U.S. Cl.

USPC **D21/333**; D14/218; D13/168

(58) **Field of Classification Search**

USPC D10/78, 70, 65; D13/154, 153, 168,
D13/133; D14/218, 205, 155, 225, 226,
D14/247; 455/557, 566, 569.1; 379/420.04;
439/369; D21/333, 332, 331

(57) **CLAIM**

The ornamental design for a game controller, as shown and described.

DESCRIPTION

FIG. 1 is a front perspective view of a game controller, showing our design;

FIG. 2 is rear perspective view thereof;

FIG. 3 is a front view thereof;

FIG. 4 is a rear view thereof;

FIG. 5 is a side view thereof;

FIG. 6 is an opposing side view thereof;

FIG. 7 is a top view thereof; and,

FIG. 8 is a bottom view thereof.

The broken lines in the figures depict portions of the game controller that form no part of the claimed design.

1 Claim, 3 Drawing Sheets
